UNITED STATES PATENT OFFICE.

HENRY ROBERTS, OF PITTSBURG, PENNSYLVANIA.

WIRE-ROD MILL.

SPECIFICATION forming part of Letters Patent No. 392,364, dated November 6, 1888.

Application filed April 23, 1888. Serial No. 271,593. (No model.)

To all whom it may concern:

Be it known that I, HENRY ROBERTS, of Pittsburgh, in the county of Allegheny and State of Pennsylvania, have invented a new and useful Improvement in Wire-Rod Mills; and I do hereby declare the following to be a full, clear, and exact description thereof.

In rolling metal rods in a mill as now commonly practiced it is customary to employ a series of trains of rolls set in line with each other and to pass the metal back and forth between these rolls. As the metal is reduced in diameter and increased in length, there is always difficulty in controlling it and preventing it from kinking, especially so when it is attempted to roll more than one rod at a time in a single mill. For this purpose it has been usual to employ boys, who stand with hooks opposite to the rolls and guide the elongating metal loop with a view of preventing it from kinking or injuring the workmen. The work of these boys is very dangerous, and requires the closest attention, and therefore the wages paid them are quite high. Besides this, the least neglect on their part is apt to cause the kinking of the rod, and when this happens the delay in its passage through the mill chills the metal and unfits it for use, necessitating the cutting of it into pieces for scrap.

My present invention is an improvement on inclined floors adapted to diminish the evils before recited; and it consists in placing over the inclined guide-floor an elevated horizontal platform or floor. The wire loop travels on the inclined floor below, and this leaves the horizontal floor unobstructed for the ordinary operations of the mill, the workmen being enabled to walk thereon in comparative security.

It also consists in providing the floor of the mill with a projection or stop having a curved end, over which the metal loop passes and around which it is drawn by the action of the rolls. The effect of this projection is to straighten the metal rod and to remove from it kinks or bends, and to compel the rod to travel in a regular course from one pair of rolls to the next.

The purpose of these features of my invention is to save time in the work of rolling the rods, to enable a great deal of the labor to be

dispensed with, and to save room in the mill-building. All these elements are important factors in the cost of manufacture of the rods, and my invention is therefore one of real importance and value. 55

The invention is illustrated in the accompanying drawings, in which—

Figure 1 is a plan view of a rod-rolling mill constructed according to the principles of my invention, one of the plates of the horizontal floor of the mill being removed to permit the inclined floor to be seen. Fig. 2 is a vertical longitudinal section on the line *x* *x* of Fig. 1. Fig. 3 is a vertical cross-section on the line *y* *y* of Fig. 1. Fig. 4 is a vertical cross-section on the line *z* *z* of Fig. 1.

Like symbols of reference indicate like parts in each.

In the drawings, 2 and 3 represent two adjacent pairs of rolls of a wire-rod mill, and 4 represents the floor of the mill on the delivery side of the rolls 2. This floor is inclined, the inclination having preferably a fall of about eleven feet in sixty, as shown in Fig. 2, 75 though the inclination may be greater or less than this.

5 is the ordinary curved guide or trough, which extends from the rolls 2 to the rolls 3 and which directs the end of the loop from one 80 pair of rolls to the other, and 8 is an open trough on the inclined floor extending transversely from the delivery side of the rolls. As the rod passes between the rolls, the enlarging loop escapes from over the guide and passes 85 down the inclined floor of the mill, one branch of the loop traveling within the guide-trough 8. The guide-trough 8 is smooth, so that it shall offer as little resistance as possible to the passage of the loop. Heretofore it has been 90 proposed to use a guide of this general character, but with a corrugated or cross-ribbed bottom; but I have found that this feature is a disadvantage.

Over a part or the whole of the inclined 95 floor is a horizontal floor, 6, which is supported by suitable beams, 7. This affords a covering for the inclined floor, and as the metal travels beneath the horizontal floor the workmen may pass back and forth on it with comparative 100 freedom from danger and without interfering with the operations of the mill. A space, *b*, is

left at the end of the horizontal floor for free passage of the wire loop beneath it. Between the opening *b* and the rolls the inclined floor is uncovered, and between the guide - trough 5 8 on one side and the other side of the inclined floor is a raised shelf, 10, at the side of which is a trough or gutter, 11, extending from the pair of rolls 3. The last-named gutter 11 is covered by a plate, 12, (preferably 10 integral with the shelf 10,) but is provided with an opening at the top, which allows the entrance of one branch of the wire loop into the gutter.

I believe I am the first to use a covered 15 guide - trough having an opening at the top, and desire to claim it broadly, since it may be used to advantage without the other elements of the combination, which I show.

The use of the gutter 11, in connection with 20 the trough on the other side of the shelf 10, is of great utility, because it keeps the branches of the wire loop separate and prevents its entanglement. The cover-plate 12 is useful, because it keeps the end of the wire loop from 25 flying up, and thus prevents entanglement when more than one loop is passed through at a single time. The side of the trough 8, between the rolls 2 and the opening *b*, is stepped, as shown in Fig. 4, the purpose of the steps 30 being to prevent the wire from rising out of the trough and to prevent the loops from tangling when two or more are passing at the same time.

For the purpose of affording access to remove scrap, which may accumulate in the space 35 beneath the horizontal floor, I may provide the horizontal floor with a trap or man-hole, or an opening may be left at the bottom of the inclined floor, as may be the more convenient.

40 On the inclined floor 4—preferably about midway—I place a projection or stop, 9, which is preferably inclined upwardly from the floor in a direction away from the rolls, and is curved at the end, as shown in Figs. 1 and 2. The 45 elongating metal loop passes over this projection and encircles it, and when the rear end of the loop emerges from the rolls 2 it is compelled by this projection to pass entirely around it. The loop is thus prevented from 50 kinking, any unevenness in the loop is straightened, and the curvature of the end prevents cutting of the loop in its passage.

I am aware that heat-retaining boxes have been sunk in mill - floors to receive coiled 55 billets, and that rod tubes or pockets have been sunk in mill-floors to receive and retain the heat in rods as they passed from the rolls, and I do not herein claim any of said devices or the principles involved therein.

Further, I am aware that inclined troughs 60 or "overfeed-regulators" have been provided to conduct the loop from the bite of the rolls to the usual horizontal mill-floor, so as to counteract the tendency of the sides of the loop to bend inward toward each other and become entangled, and I do not herein broadly 65 claim such overfeed-troughs, which are features independent of and leading to the floor proper; but

What I claim is—

70 1. In a wire-rod mill, the combination, with two sets of rolls arranged to have different lines of feed, of an inclined sub-floor leading to and from said pairs of rolls, and a covering-floor arranged over said inclined sub-floor, substantially as and for the purposes specified.

75 2. In a wire-rod mill, the combination, with two sets of rolls arranged to have different lines of feed, of an overfeed-regulator leading from the rolls to the floor, an inclined receiving-floor, and a curved projection or stop arranged on said floor at or near the end of the loop-path, substantially as and for the purposes described.

80 3. In a wire-rod mill, the combination, with two sets of rolls arranged to have different lines of feed, of an inclined sub-floor, an upper or covering floor, and a loop-stop arranged on the sub-floor under the covering-floor, substantially as and for the purposes specified. 85 9c

4. In a wire-rod mill, the combination, with two sets of rolls arranged to have different lines of feed, of an inclined loop-trough having at one side an open passage and at the other a partially - covered passage, substantially as and for the purposes specified. 95

5. In a wire-rod mill, the combination, with two sets of rolls arranged to have different lines of feed, of a loop-trough provided with lateral steps or risers, substantially as and for the purposes specified. 100

6. In a wire-rod mill, the combination, with the rolls, of a longitudinally - inclined guide-trough having a laterally-inclined side, substantially as and for the purposes specified. 105

7. In a wire-rod mill, the combination, with two sets of rolls, of a loop-trough having the gutter 11 and a plate, 12, which partially covers said gutter, substantially as and for the purposes specified. 110

In testimony whereof I have hereunto set my hand this 5th day of April, A. D. 1888.

HENRY ROBERTS.
